UNITED STATES PATENT OFFICE.

LUDELLA PENNY, OF WILSON, NORTH CAROLINA.

COLLAR-SUPPORT.

1,102,681.

Specification of Letters Patent.

Patented July 7, 1914.

Application filed November 7, 1911. Serial No. 659,068.

To all whom it may concern:

Be it known that I, LUDELLA PENNY, a citizen of the United States, residing at Wilson, in the county of Wilson and State of North Carolina, have invented a new and useful Collar-Support, of which the following is a specification.

This invention relates to collar supporters, its principal object being to provide an inexpensive device of this character which can be readily attached to a collar without showing and which will yield under downward pressure so as to produce no discomfort to the wearer.

15 A further object is to provide a supporter which can be easily adjusted to fit collars of different heights.

A further object is to provide a supporter the end portions of which are extended in 20 the direction of the length of the upper and lower edges of the collar, thus directly supporting an extensive area of the collar and, at the same time, preventing injury to the wearer or to the collar by the ends of the 25 supporter.

A still further object is to provide a supporter which does not detract from the appearance of the collar and which, by being properly covered, can be used with an ordinary lace collar.

With the foregoing and other objects in view which will appear as the description proceeds, the invention resides in the combination and arrangement of parts and in 35 the details of construction hereinafter described and claimed, it being understood that changes in the precise embodiment of the invention herein disclosed can be made within the scope of what is claimed, 40 without departing from the spirit of the invention.

In the accompanying drawings the preferred form of the invention has been shown.

45 In said drawings:—Figure 1 is a perspective view of the supporter, a portion of a collar being shown in engagement therewith. Fig. 2 is an enlarged detail view of the supporter. Fig. 3 is a view of the support connected to a portion of a lace collar having a design corresponding with that of the support. Fig. 4 is an enlarged elevation of a portion of the support and showing how the same may be wrapped with thread. 55 Fig. 5 is a view similar to Fig. 4 and show-

ing a portion of the support with an enamel covering thereon, a portion of this covering being broken away.

Referring to the figures by characters of reference 1 designates a coiled loop of 60 spring wire having oppositely extending yielding arms 2 defining ogee curves, the outer end of each arm merging into an eye 3 from which extends a finger 4. The fingers at the two ends of the support are preferably normally parallel and the free end of each finger is bent back, as at 5, so as to present a blunt end which will not puncture a fabric or injure the user of the supporter. Furthermore these blunt ends form enlargements or loops which tend to retard the withdrawal of the fingers from the hems in which they are seated.

In the drawings a portion of a collar has been indicated at A and this collar is provided with the usual hems a along the upper and lower edges thereof. The upper hem is adapted to receive the upper finger 4 of the supporter, while the lower end is adapted to receive the other finger 4. When the supporter is in position it contacts with the inner surface of the collar and, in view of the fact that the supporter is formed of spring wire, it will be apparent that the fingers 4 and the coiled portion 1 of the 80 supporter will operate to hold the collar taut. By bending the coil 1, the supporter can be shortened or lengthened to fit collars of different widths. It will be seen that it is unnecessary to sew the supporter to a collar and it will furthermore be apparent that, as the fingers 4 extend along lines substantially parallel with the upper and lower edges of the collar, they will support extensive areas of the collar and will not stick 85 through the collar or in the wearer.

As shown in Figs. 3 and 4 the support can be wrapped with silk or any suitable thread, such as shown at 6 and which is of the same color as the collar 7 to which the support is attached. Furthermore as shown in Fig. 3 the support can be so shaped as to appear as a design in the lace. Instead of covering the support with thread, the same can be provided with an enamel covering 8 of any desired color, as shown in Fig. 5.

What is claimed is:—

A supporter for lace collars and the like, formed in a single length of spring wire 110

and comprising upper and lower fingers substantially parallel, a coil at one end of each finger, a loop at the other end of each finger, an arm extending from each coil, 5 said arms being similar and oppositely disposed and each forming a compound curve, the said arms merging in a coiled loop equidistant from the fingers and disposed in the same plane with the arms and fingers, the

said fingers being extended in opposite directions from their respective coils.

In testimony that I claim the foregoing as my own, I have hereto affixed my signature in the presence of two witnesses.

LULA PENNY.
